TREATMENT OF HYDROCARBONS

Vladimir Ipatieff and Vasili Komarewsky, Chicago, Ill., assignors to Universal Oil Products Company, Chicago, Ill., a corporation of Delaware

No Drawing. Application August 16, 1935,
Serial No. 36,560

4 Claims. (Cl. 260—167)

This invention relates to the treatment of saturated hydrocarbons such as paraffins and naphthenes representing the groups of chain and cyclic hydrocarbons respectively and, in a more 5 specific sense, is concerned with a process involving the interaction of paraffins and naphthenes in the presence of selected catalysts and under properly chosen conditions of temperature and pressure to form mixed hydrocarbon derivatives.

Hydrocarbons of the character involved in the process of the present invention are the less reactive of the hydrocarbon classes in contrast to the more reactive olefins and aromatics. In the 10 case of the paraffins, represented by the general formula C_nH_{2n+2} , they show substantially no reactivity with even strong acids like sulfuric unless the temperature is raised to a point where the oxidizing properties of the acid come into play. 15 The cyclic naphthalene hydrocarbons having the general formula C_nH_{2n} also require oxidizing temperatures for interaction with sulfuric acid though these temperatures may be somewhat lower than those corresponding to paraffin hydrocarbons with the same number of carbon atoms.

Both paraffin and naphthalene hydrocarbons ex-

to paraffins may be somewhat higher in the latter case. Toward each other these two groups are substantially unreactive in the absence of catalysts below cracking temperatures and it is with a catalytic process which enables the interaction of these two groups at relatively low temperatures that the process of the present invention is concerned.

In one specific embodiment the invention comprises reacting paraffin hydrocarbons with naphthalene hydrocarbons in the presence of phosphoric acid at elevated temperatures and pressures to produce mixed derivatives.

According to the present invention any naphthalene may be reacted with any paraffin, any single naphthalene may be reacted with any mixture of paraffins or any single paraffin may be reacted with any mixture of naphthalenes while using a phosphoric acid as a catalyst. It is preferable to use as catalysts the acids of phosphorous in which this element has a valence of 5, and for purposes of reference the names, formulas and common properties of the ortho and pyrophosphoric acids which are the most serviceable in the present instance are given below.

Name			M. P. ° C.	Dec. ° C.
Orthophosphoric	H_3PO_4	$P_2O_5 \cdot 3H_2O$	38.6	
Pyrophosphoric	$H_4P_2O_7$	$P_2O_5 \cdot 2H_2O$	61	Loses $\frac{1}{2} H_2O$ at 213

ist in high percentages in the relatively low boiling fractions of petroleums of either a paraffinic or a mixed base origin, and it may even be said that they preponderate in the lower distillation products of petroleums of a distinctly asphaltic character even though the ratio of naphthenes

For further purposes of reference and with no intent of unduly limiting the scope of the invention the following tables are introduced to indicate some of the compounds of both the paraffin and naphthalene series of hydrocarbons which may be caused to interact.

Compound	Formula	Boiling point ° C.	Melting point ° C.
Propane	$CH_3CH_2CH_3$	*-45	
Normal butane	$CH_3CH_2CH_2CH_3$	+1	
Trimethyl methane	$CH_3CH(CH_3)_2$	-17	
Normal pentane	$CH_3(CH_2)_3CH_3$	+38	
Dimethyl ethyl methane	$CH_3CH_2CH(CH_3)_2$	+30	
Tetramethyl methane	$C(CH_3)_4$	+9	
Normal hexane	$CH_3(CH_2)_4CH_3$	+71	
Methyl diethyl methane	$CH_3CH(CH_2)_2CH_3$	+64	
Dimethyl propyl methane	$CH_3CH_2CH_2CH(CH_3)_2$	+62	
Di-isopropyl	$(CH_3)_2CH_2CH(CH_3)_2$	+58	
Trimethyl ethyl methane	$CH_3CH_2C(CH_3)_3$	+49	
Heptane	C_7H_{16}	98.4	
Octane	C_8H_{18}	125.5	
Nonane	C_9H_{20}	149.5	-51
Decane	$C_{10}H_{22}$	173	-32
Undecane	$C_{11}H_{24}$	194.5	-26.5
Dodecane	$C_{12}H_{26}$	214	-12

	Compound	Formula	Boling point °C.	Melting point °C.
5	Tridecane	C ₁₃ H ₂₈	234	-6.2
	Tetradecane	C ₁₄ H ₃₀	262.5	+5.5
	Pentadecane	C ₁₅ H ₃₂	270.5	+10
	Hexadecane	C ₁₆ H ₃₄	287.5	+18
	Heptadecane	C ₁₇ H ₃₆	303	+22.5
	Octadecane	C ₁₈ H ₃₈	317	+28
	Nonadecane	C ₁₉ H ₄₀	* 330	+32
10	Eicosane	C ₂₀ H ₄₂	206	+36.7
	Heneicosane	C ₂₁ H ₄₄	215	+40.4
	Docosane	C ₂₂ H ₄₆	224.5	+44.4
	Tricosane	C ₂₃ H ₄₈	234	+47.7
	Tetracosane	C ₂₄ H ₅₀	243	+51.1
	Heptacosane	C ₂₇ H ₅₆	270	+59.5
	Heptadecane	C ₂₇ H ₅₆	302	+68.1
	Dotriacontane	C ₃₁ H ₆₀	310	+70.0
15	Pentatriacontane	C ₃₅ H ₆₇	331	+74.7
	Dimyricyl	C ₃₆ H ₇₂		+102

	1,4-methyl-sio-propyl-cyclo-hexane, hexahydro-cynol		167

* @ 15° C.

40 Owing to the fact that there are paraffin hydrocarbons which are normally gaseous, liquid and solid and also naphthalene hydrocarbons which exist in the same three phases, it is evident that the details of procedure when carrying out the process are capable of considerable modification, when it is also considered that varying temperatures and pressures may be used depending upon the reactivity of the various compounds, the proportions in which they are used and the character of the results desired.

45 In a simple method of carrying out the process, liquid paraffins and liquid naphthalenes are mixed and contacted with orthophosphoric acid of approximately 90% concentration in exteriorly heated rotating bombs. The temperature necessary for effecting interaction will vary with the proportions and the molecular weight of the interacting paraffins and naphthalenes respectively 50 so that only general ranges can be given which are approximately 700 to 900° F. The pressures generated will again depend upon the type and character of the interacting constituents and the proportions in which they are employed, though 55 it is common observation that the pressure may be atmospheric or may rise to as high as 100 atmospheres or higher at temperatures in the neighborhood of 800° F. due partly to the evolution of fixed gases resulting from the decomposition of both groups of hydrocarbons.

60 65 70 Continuous operations may be conducted in the case of liquid paraffins and naphthalenes by pumping them along with phosphoric acid through tubular heating elements in which they are brought up to the proper reaction tempera-

ture and then discharging the reaction products 20 into settling chambers in which the phosphoric acid is separated as a lower layer while the lower boiling hydrocarbon products are released as vapor and fractionated under reduced pressure and any unvaporized hydrocarbon products are 25 drawn off with the phosphoric acid.

25 In cases involving the interaction of gaseous paraffins and liquid naphthalenes, several alternative modes of operation will suggest themselves to those familiar with these types of commercial 30 operation. For example, in batch operation paraffinic gases may be pumped continuously into heated mixtures of naphthalenes and phosphoric acid until the desired degree of reaction has taken place or gases and liquids may be vaporized and 35 passed upwardly countercurrent to descending streams of phosphoric acid in towers containing inert baffling or spaced filling material. The process is not limited to the particular type of 40 mechanical arrangement of apparatus which may be employed to effect the desired reactions.

45 Observation of a considerable number of reactions typical of the present process indicates that what may be termed a destructive alkylation occurs. There is a variable amount of decomposition of each of the reacting compounds, both paraffinic and naphthalenic with the formation of transient radicals which results to form mixed derivatives of the general character of alkylated naphthalenes. This necessarily involves some loss 50 of hydrogen and there are also formed some low boiling paraffinic gases such as methane and ethane owing to the lack of 100% efficiency in the reactions. The process is of especial value in increasing the antiknock value of naphthalenic 55 distillates by the use of low boiling paraffin hydrocarbons from methane to hexane, such as are normally present in natural and refinery gases.

60 The following example is given to indicate the character of the results obtainable by the use of the present process though it is not intended for the purpose of correspondingly limiting the scope of the invention.

bons boiling within the range of 230-340° F. By resubjecting the unaffected hexane and cyclohexane to the same treatment after the removal of the alkylated reaction products it was found possible to increase the yield of alkylated aromatic and naphthenic reaction products to approximately 60% of the original reacting constituents. These products were directly utilizable for blending material for increasing the anti-knock value of gasoline.

The above specification and numerical data have been given to indicate the general character of the invention and to illustrate the results obtainable by its use although neither section is intended to be unduly limiting.

We claim as our invention:

1. A process for producing alkylated hydrocarbons which comprises reacting a paraffin and a naphthenic hydrocarbon at destructive alkylation

temperature of from about 700° F. to 900° F. and in the presence of orthophosphoric acid.

2. A process for producing alkylated hydrocarbons which comprises reacting a paraffin and a naphthenic hydrocarbon at destructive alkylation 5 temperature of from about 700° F. to 900° F. and in the presence of pyrophosphoric acid.

3. A process for producing alkylated hydrocarbons which comprises reacting a paraffin and a naphthenic hydrocarbon at a temperature of 10 from about 700° F. to 900° F. and in the presence of a phosphoric acid.

4. A process for producing alkylated hydrocarbons which comprises reacting a paraffin and a naphthenic hydrocarbon at a temperature of 15 from about 700° F. to 900° F. and in the presence of a phosphoric acid in which the phosphorus has a valence of 5.
